UNITED STATES PATENT OFFICE.

ISAAC N. CHERRY AND ROBERT N. CHERRY, OF JERSEY CITY, NEW JERSEY.

HAND RATCHET-DRILL.

SPECIFICATION forming part of Letters Patent No. 240,575, dated April 26, 1881.

Application filed August 14, 1880. (Model.)

To all whom it may concern:

Be it known that we, ISAAC N. CHERRY and ROBERT N. CHERRY, of Jersey City, in the county of Hudson and State of New Jersey, have jointly invented a Self-Feeding Ratchet Hand-Drill, of which the following is a specification, reference being had to the accompanying drawings, forming part of the same, in which—

10 Figure 1 is a longitudinal central section of a drill-stock containing our invention. Fig. 2 is an external side view of the same. Fig. 3 is a cross-section on line $x-x$, Fig. 1; and Figs. 4 to 8, inclusive, are detached views of several 15 detached parts, to be particularly described.

Our invention relates to that class of hand-drills in which rotary motion is given to the drill-stock by a reciprocating handle that swings loosely on the drill-stock, and that 20 communicates motion to the stock by means of a ratchet on the stock and a pawl connected with the handle; and, more particularly, to the combination, with the stock and handle, of the described attachments, whereby the movement 25 of the handle is made to automatically accomplish a feed-motion of the drill, thus rendering the instrument self-feeding.

A is the drill-stock, on which are formed or made fast two ratchet-wheels, a b , the ratchet- 30 teeth on each being reversed from those of the other.

B is the handle, arranged to swing loosely on the stock, the inner end being composed of two plates, c and d , one on each side of the 35 said ratchet-wheels, the upper plate, c , being detachable and secured to the other and to the handle by screws or rivets. The handle is provided, preferably, with two pawls, e e' , as shown plainly in Fig. 3, one, e , to engage with 40 wheel b , and the other, e' , with wheel a . The pawls are pivoted at e^2 and e^3 in plates c and d , and are pressed into engagement and held out of engagement with the ratchet-wheels by the springs f f' . These springs may be made 45 of a single piece of metal doubled round the abutment g , and between it and the abutment g' , the free ends f and f' acting against the pawls e e' , what is therefore substantially a single spring being made to perform the func-

tions of two springs. C is the feed-screw that 50 works in a female screw in the upper end of the drill-stock.

The instrument, as far as described, will be readily recognized as the ordinary hand ratchet-drill. With this we combine our automatic feed-works, which we will now proceed to describe:

Upon the drill-stock, above the handle, we place an eccentric double sleeve, h h' , (this is made double for a purpose to be presently 60 described,) the two parts together constituting, in fact, one sleeve, which is fitted to revolve loosely upon the stock, and is retained in place by a collar, i , (represented detached from the stock in Fig. 6,) which is secured upon the upper end of the stock by screws. Upon this eccentric-sleeve we place another sleeve, h^2 , which sets down over it and rests upon a shoulder formed on it, as shown in Fig. 1. It is fitted loosely upon the eccentric-sleeve, so that the eccentric may revolve within it, and they are secured together by screws, one of which is seen in Fig. 1, (marked j ,) and the heads of two of them are seen in Fig. 2, (also marked j .) A groove is cut in the external surface of the eccentric, as seen in Fig. 1, into which the inner ends of the said screws enter loosely, so as to leave the eccentric free to revolve in the sleeve h^2 , while they prevent them from being separated. A little distance below the upper end of 70 the sleeve h^2 , on its interior wall, is an annular rim or projection, k , which rests upon the upper end of the sleeve h . The circular opening through this annular projection is somewhat 75 larger than the diameter of the screw C, so as to permit of the motion on the screw of sleeve h , which is given to it by the revolving of the eccentric. In this annular projection is a notch, l , as seen in Fig. 8, into which a lug, m , projects from the upper face of the collar i . This 80 lug, as is evident, so connects the sleeve h^2 with the stock A that it must revolve with it.

D is a ratchet-wheel having a hub, as shown in Fig. 1, through which passes the screw C, the central opening through which being just 85 large enough to permit the said screw to pass loosely through it. On the inner face of the hub is a feather, which works loosely in a lon-

5 longitudinal groove in the screw C, so that the screw must be turned by the turning of the said ratchet-wheel. This ratchet-wheel rests upon the upper face of the annular projection k, and the lower end of its hub projects into the central opening of this projection, the hub being smaller than the opening, so as to permit the shifting of the sleeve h² from side to side.

10 Into the upper end of the sleeve h² is fitted a disk, E, having a large central opening, with an upward-projecting neck or flange, n, around said opening. This disk, between which and the annular projection k is placed the ratchet-
15 wheel D, is secured to the sleeve h² by screws passing down into the said annular projection k. It carries two pawls, o and o', that are pivoted in holes in the disk on opposite sides, near its perimeter, and are arranged to engage, one
20 on each side, with the teeth of the ratchet-wheel D, and are pressed into engagement with said wheel by the springs p and p', as seen in Fig. 4. From the upper face of each of these pawls, between its pivot and the opposite end,
25 a small stud, r and r', as shown in Fig. 1, projects up through a slotted hole in the disk E, for a purpose to be presently described.

F is a cap having a central opening, which fits down snugly around the upward projection n, and rests upon the upper end of the sleeve h², to which it is secured by screws s s'. On the under face of this cap are formed two recesses, q and q', as shown in Fig. 5, that are so shaped as to act as cams upon the studs r and r'. The screws s s', which hold this cap upon the sleeve, pass through slotted holes in the cap and bottom in the sleeve, so as to leave the cap free to be rotated or shifted to the right and left on its seat to the extent of the 35 slotted holes. The studs r and r' are acted upon by the inner walls of the recesses q and q' to take the pawls o and o' out of engagement with the ratchet-wheel D when the cap is shifted in one direction, and to permit them 40 to engage with said ratchet-wheel when shifted in the opposite direction, thus putting on or taking off the feed.

t and t' represent rubber packings put into recesses in the under face of the cap F, which, 50 by projecting slightly below the said surface, will give a little easy friction between the cap and its seat, thus holding it still thereon, while at the same time it is free to be rotated or shifted.

55 Now, it is evident that when the eccentric sleeve, heretofore described, is held at rest or prevented from revolving while a rotary motion is given to the stock, and with it to the sleeve h², the said sleeve h² will have communicated to it by the eccentric h a motion similar to that of the strap upon an eccentric usually employed to procure from the eccentric a rectilinear motion, which will be equivalent to the reciprocation of the said h² from side to side, and that as it thus shifts in one direction one of the pawls, o, will rotate the ratchet-

10 wheel D to the extent of that movement, and that as it moves in the opposite direction the other pawl will give a similar movement of the ratchet-wheel in the same direction, and 70 that thereby a feed-movement will be communicated to the screw C at each revolution of the stock, due to the eccentricity of the sleeve heretofore described. This eccentric-sleeve is made double, for the purpose of regulating 75 the rate of the feed. Both of the sleeves, h and h', are eccentric, one, h', being placed within the other, h. When both long diameters of the eccentric coincide the resulting eccentricity will be the greatest, and when the 80 said diameters are opposite each other the resulting eccentricity is least, or nothing at all, the perimeter of the sleeve h becoming then concentric with the stock. As h is then shifted upon h', the eccentricity of the perimeter of h 85 may be increased or decreased at pleasure, and consequently the rate of feed may be thus adjusted. When the two eccentric-sleeves are set for any given rate of speed they are secured in such adjustment by a set-screw, u.

90 Index figures, letters, or lines may be made on the outer face of the sleeves h and h', as seen in Fig. 2, so that the workman may conveniently make such adjustment.

Fig. 7 represents a square bushing, intended 95 to fit into the lower end of the drill-stock to receive a round-shanked drill, a straight flattened notch being cut down into the upper end of the bushing, as shown in said figure, into which the flattened end of the round 100 shank may project, whereby the turning of the drill with the bushing is secured.

In operating this drill the workman simply inserts a rod in a hole, v, provided to receive it in sleeve h, and holds it, together with sleeve 105 h', at rest while he vibrates the handle back and forth in the usual way.

What we claim as our invention, and desire to secure by Letters Patent, is—

1. The combination, with a hand-ratchet-drill stock, of the feed-works described, consisting of the eccentric-sleeve, the sleeve h², carrying the disk E, with its pawls o and o', the ratchet-wheel D, and the screw C, all as and for the purpose described.

2. The combination, with a ratchet-drill stock, of the eccentric-sleeve h, the concentric sleeve h², to which are pivoted the pawls o o', one or both, the ratchet-wheel D, with which said pawls engage, and the screw C, all constructed and arranged to operate as and for the purpose described.

3. The combination, with a ratchet-drill stock, of the eccentric-sleeve h and h', the concentric sleeve h², to which are pivoted pawls o and o', one or both, the ratchet-wheel D, with which said pawls engage, and the screw C, all constructed and arranged to operate as and for the purpose described.

4. The combination, with a hand-ratchet-drill stock, of the screw C, the ratchet-wheel D, the eccentric-sleeve described, sleeve h²,

the disk E, carrying the pawls *o* and *o'*, springs *p* and *p'*, and the cap F, having the recesses *q* and *q'*, constructed and arranged as described, so that the shifting of the said cap on its seat 5 will put on or take off the feed, all as described.

5. The combination, with a hand-ratchet-drill stock, of the handle B, a suitable ratchet wheel or wheels, the swinging pawls *e* and *e'*, the springs *f* and *f'*, made of a single piece of metal,

and the abutments *g* and *g'* between the plates *c* and *d*, all as described, and for the purpose specified.
